ANTENNA LEAD CLIP

Edwin C. Auld, Jr., Pasadena, and Robert E. Imus, Sierra Madre, Calif. (both % R. E. Imus, 839 Woodland Drive, Sierra Madre, Calif.)

Filed July 22, 1960, Ser. No. 44,689

3 Claims. (Cl. 174—154)

This invention relates to antenna lead clips; that is, to devices for supporting antenna leads or other electrical lines in spaced relation to a roof or other surface.

Included in the objects of this invention are:

First, to provide an antenna lead clip which incorporates novel means for clamping a roof shingle or the like to provide an upright support, and means for receiving and securing an antenna lead of either the circular or parallel wire type.

Second, to provide an antenna lead clip which may be installed and secured to an antenna lead without the use of tools.

Third, to provide an antenna lead clip in which the antenna lead receiving means includes an insulating element partially rotatable between a lead receiving position, wherein the antenna may be readily inserted or removed by radial movement into or out of the insulating element, and a securing position wherein the lead is tightly gripped and held from contact with metal.

Fourth, to provide an antenna lead clip wherein the clamping means is adapted to fit various types and thicknesses of shingles.

Fifth, to provide an antenna lead clip which although capable of providing a permanent support for an antenna lead or the like, may be readily removed or changed in position, or arranged to permit adjustment of the antenna lead.

With the above and other objects in view, as may appear hereinafter, reference is directed to the accompanying drawings in which:

FIGURE 1 is a side view of the antenna lead clip shown secured to a roof shingle and showing fragmentarily an antenna lead shown secured in the antenna lead clip;

FIGURE 2 is a sectional view through 2—2 of FIGURE 1 showing the base portion of the antenna lead clip;

FIGURE 3 is a fragmentary sectional view through 3—3 of FIGURE 1 illustrating the manner in which the antenna lead is secured in the antenna lead clip;

FIGURE 4 is a similar fragmentary sectional view with a portion shown in elevation showing the manner in which the clamping disk of the antenna lead clip is positioned to receive an antenna lead;

FIGURE 5 is an enlarged fragmentary sectional view taken through 5—5 of FIGURE 4 showing the opposing walls of the antenna lead receiving slit;

FIGURE 6 is a fragmentary sectional view similar to FIGURE 3, showing a modified form of the antenna lead retaining disk, the disk being shown in its lead securing position;

FIGURE 7 is a partial sectional, partial end view thereof, showing the lead receiving disk in its position to receive an antenna lead.

FIGURE 8 is a fragmentary sectional view similar to FIGURES 3 and 6, showing a further modified form of antenna lead receiving member, with the antenna lead shown as it appears when secured.

FIGURE 9 is a fragmentary end elevational view of the FIG. 8 embodiment, showing the position of the disk when disposed so as to receive an antenna lead.

FIGURE 10 is a fragmentary sectional view similar to FIGURE 3, showing a still further modified form of

2

the antenna lead receiving disk, the disk being shown in its position for securing the antenna lead.

FIGURE 11 is a partial sectional, partial elevational view of the FIG. 10 embodiment, showing the modified antenna lead receiving member in position to receive the antenna lead.

The antenna lead clip includes a triangular base loop 1 formed of wire having some degree of springiness. One end of the loop is turned upwardly, as indicated by 10 2, for a distance slightly greater than the thickness of a typical shingle S, as shown in FIGURE 1. The upper end of the portion 2 is bent to form a clamp element 3, having one or more steps or shoulders 4 and downwardly sloping portions 5 therebetween. The clamp element 3 forms with the base loop 1 a yieldable clamping means which is adapted to receive shingles of various thicknesses. That is, the clamp means is adapted to fit relatively thin shingles or relatively thick shakes.

The clamp element 3 is bent upwardly near the side of 20 the loop 1, remote from the upturned apex 2, to form an upturned stem 6 which preferably extends perpendicular to the base loop 1. The upper extremity of the stem 6 terminates in an open loop 7 of circular configuration with the stem 6 disposed in radial relation therewith, and 25 with the extremity of the loop 7 forming with the stem an opening 8.

The loop 7 is adapted to receive a disk member 9 having an annular groove 10 which receives the loop 7 so that the disk member is capable of rotation within the 30 loop 7 but is held against axial displacement. In order to rotate the disk member 9, one axial side thereof may be provided with handle lugs 11 as shown in FIGURE 1. The disk member is provided with a radial slit 12 extending somewhat more than half way through the disk member and terminating at its inner end in an enlarged opening 13.

The slit is adapted to receive an antenna lead L of the type comprising two parallel wires connected by a web; or the opening 13 may receive a round wire lead.

The sides of the radial slit 12 may converge towards 40 each other from the axial ends of the disk member and be provided with axially displaced ribs 14 as shown best in FIGURE 5. With this arrangement, when the sides of the slit are pressed towards each other as will be 45 described hereinafter, the axially offset ribs tend to produce a rudimentary S bend in an antenna lead L inserted in the slit.

The periphery of the disk member 9, at one side of the radial slit 12, is provided with a notched portion 15.

50 At the opposite side of the radial slit the annular groove 10 is provided with a radial bulge 16, as is shown best in FIGURE 4.

Operation of the antenna lead clip disclosed in FIGURES 1 through 5 is as follows:

The triangular base loop 1 is inserted under a shingle or shake S as shown in FIGURE 1 so that the clamp element 2 bears on top of the shingle or shake and support the stem 6 in substantially perpendicular relation with the surface of the roof. The disk member 9 is rotated so 60 that the radial slit 12 registers with the opening 8 in the loop 7 as shown in FIGURE 4. The antenna lead L is then inserted radially into the slit whereupon the disk 9 is rotated to a position such as shown in FIGURE 3. In doing so the bulge 16 is distorted into the notch 15 as 65 shown in FIGURE 3, so as to close the slit 12 and prevent the antenna lead from moving radially into contact with the loop 7. The dimensions of the bulge 16 may be such that in order for the disk 9 to turn to the position 3 the loop 7 must expand slightly so as to apply and increase constrictive force on the disk member 9 and compress the walls of the slit 12 tightly against the opposite 70 sides of the antenna lead so that the antenna lead is firmly

held and may be forced into a rudimentary S configuration by reason of the ribs 14.

Reference is now directed to the construction shown in FIGURES 6 and 7. The construction here shown is essentially the same as the previously described structure except that in place of the notch 15 the groove 10 is provided with an arcuate recess 17 and in place of the bulge 16 there is provided a flexible tongue 18 adapted to fold into the arcuate recess 17 as the disk member is turned from the position shown in FIGURE 7 to the position 10 shown in FIGURE 6. With this arrangement the tongue 18 crosses over the end of the radial slit 12 and completely closes the end so that the antenna lead cannot move radially into contact with the loop 7. As in the first described structure the tongue 18 may be slightly larger 15 than the recess 17 so that on turning of the disk member to the position shown in FIGURE 6 a constrictive force is applied causing the walls of the slit 12 to grip the antenna lead.

Reference is now directed to the construction as shown in FIGURES 8 and 9. In this construction an oval-shaped loop 7a is substituted for the circular open loop 7 and an oval-shaped disk 9a is substituted for the disk 9. The slit 12 is so oriented that when the major axes of the oval loop and oval disk are in coincidence the slit is exposed to the opening 8. Upon rotation of the disk 9a to a position 90° from that shown in FIGURE 9, that is to the position shown in FIGURE 8, the disk 9a is distorted 20 so that the walls of the slit grip the antenna lead.

Reference is now directed to FIGURES 10 and 11. In the construction here illustrated the loop 7 is provided with an internal bulge 19 and the bottom of the annular groove 10 is provided with a notch 20. When the bulge 19 and notch 20 are in registry the slit 12 registers with the opening 8. Upon turning the disk member 9 until the notch and bulge are out of registry, as shown in FIGURE 10, the disk is distorted so that the walls of the slit 12 grip the antenna lead and the radially outer ends of the slit are compressed sufficiently tight that the antenna lead cannot move radially into contact with the loop 7. 40

It will be observed that while the base loop 1 and clamp element 3 are particularly designed to grip a shingle or shake forming a part of a roof, the loop 1 may be slipped under a strip of siding on a vertical surface. It will also be observed that while the stem 6 is normally disposed perpendicular to the surface defined by the loop 1, it may be bent into other angular positions as may be desired.

While particular embodiments of this invention have been shown and described, it is not intended to limit the same to the exact details of the constructions set forth, and it embraces such changes, modifications, and equivalents of the parts and their formation and arrangement as come within the purview of the appended claims.

What is claimed is:

1. An antenna lead clip, comprising:
  - (a) a supporting structure having an open loop element;
  - (b) an insulation disk formed of distortable material and having a peripheral groove fitted within said loop element to permit rotation of said disk therein;
  - (c) said disk also having a radial slit adapted to register with the open side of said loop element to receive an antenna lead, and movable on rotation of said disk to a retaining position confronting a wall of said loop element;

(d) the confronting walls of said slit having axially offset ribs engageable with opposite sides of said antenna lead at axially displaced points thereon to resist longitudinal displacement of said antenna lead;

(e) and forming means operable on movement of said disk toward its retaining position to cause said disk to grip said antenna lead.

2. An antenna lead clip, comprising:

- (a) a supporting structure having an open loop element;
- (b) an insulation disk formed of distortable material and having a peripheral groove fitted within said loop element to permit rotation of said disk therein;
- (c) said disk also having a radial slit adapted to register with the open side of said loop element to receive an antenna lead, and movable on rotation of said disk to a retaining position confronting a wall of said loop element;
- (d) and means operable on movement of said disk toward its retaining position to cause said disk to grip said antenna lead;
- (e) said means including a tongue projecting radially from said disk at one side of said slit and a mating recess at the opposite side thereof, said tongue adapted to fold into said recess and close said slit on rotation of said disk to its retaining position.

3. An antenna lead clip, comprising:

- (a) a supporting structure having an open loop element;
- (b) an insulation disk formed of distortable material and having a peripheral groove fitted within said loop element to permit rotation of said disk therein;
- (c) said disk also having a radial slit adapted to register with the open side of said loop element to receive an antenna lead, and movable on rotation of said disk to a retaining position confronting a wall of said loop element;
- (d) and means operable on movement of said disk toward its retaining position to cause said disk to grip said antenna lead;
- (e) said means including a notch in the periphery of said disk and an internal bulge in the wall of said loop element, said notch and bulge adapted to register when said slit registers with the open side of said loop element and misregister when said disk is in its retaining position, whereby said bulge distorts said disk.
